(57) **CLAIM**

The ornamental design for a torque measuring instrument, as shown and described.

DESCRIPTION

FIG. 1 is a front view of the torque measuring instrument, showing the new design;

FIG. 2 is a rear view thereof;

FIG. 3 is a right-side view thereof, and the left side thereof is a mirror image of the right side thereof;

FIG. 4 is a top view thereof;

FIG. 5 is a bottom view thereof;

FIG. 6 is a front, left side, and top perspective view thereof; and,

FIG. 7 is another front, left side, and top perspective view thereof.

The broken line showing of portions of the torque measuring instrument is for the purpose of illustrating environmental structure and forms no part of the claimed design.

The torque measuring instrument may be used, for example, to measure torque that is applied to unscrew a cap from a bottle. In operation, the bottle may be placed on and secured to the fixture that is shown in broken lines in FIG. 7. As the cap is unscrewed from the bottle, the torque that is applied to the cap may be measured.
